UNITED STATES PATENT OFFICE.

CARL E. PEARSON, OF CLEVELAND, OHIO, ASSIGNOR TO THE TEAGLE COMPANY, OF CLEVELAND, OHIO, A CORPORATION OF OHIO.

ELECTRICAL CONDENSER.

Application filed March 1, 1923. Serial No. 622,021.

This invention relates to electric condensers and particularly to condensers suitable for use in primary circuits of ignition generators.

5 The chief objects of the invention are comprised in the provision of a condenser that is simple and rugged structurally, easily assembled, and effective and reliable in use.

10 Other objects, more or less ancillary to the foregoing, will be apparent from the following description in which the preferred form of construction is set forth in connection with the accompanying drawing.

15 In the drawing, Fig. 1 is a front elevation of my improved condenser as mounted on the frame structure of a magneto.

Fig. 2 is a section on the line 2—2, Fig. 1.

20 Figs. 3 and 4 are sections on the broken line 3—3, Fig. 1, showing respectively the parts as they appear before and after the securing screws are driven home.

Fig. 5 is a section on the line 5—5, Fig. 1.

25 Fig. 6 is a perspective view of the condenser parts in separated or disassembled relation so as to more clearly show the construction.

30 Fig. 7 is a face elevation and Figs. 8 and 9 are edge elevations of the conductor terminal fitting employed.

Referring in detail to the construction illustrated, 1 is a portion of the magneto metallic frame on which the condenser is mounted or supported. The condenser proper consists of a pack made up of metal foil conductor sheets 2, 3, and interposed dielectric sheets 4. The conductor sheets 2 and 3 are preferably made of tinfoil and the dielectric sheets of mica. The alternate conductor sheets 2 extend at the upper end of the pack and are folded over on the front side thereof, as shown. Similarly, the alternate conductor sheets 3 extend at the lower end of the pack and are folded over on the 45 front side thereof.

On the two ends of the pack are mounted sheet metal clips 5, 6 which are preferably formed of hard sheet brass 0.002" thick. The pack with the end clips applied is insulated from the support 1 by a sheet 7 of suitable material such as impregnated or vulcanized fibre. The condenser is secured to the support 1 by upper and lower casing sections 8 and 9 which are preferably 50 stamped from #18 gauge sheet brass and

are partially hardened. The casing section 8 is formed at one side with a socketed and apertured lug 8^a and at its other side with a similar lug 8^b. At its top side said section 8 is formed at one side with flanges 8^c, 8^d and at its left side with a flange 8^e and at its right side with a flange 8^f. In a similar manner the casing section 9 is formed with socketed and apertured lugs 9^a, 9^b, bottom flanges 9^c, 9^d, and side flanges 9^e, 9^f. The 60 casing section 8 which serves to clamp the upper part of the condenser to the support 1 is secured to the said support by means of screws 10, 11. Said casing section 8 is electrically insulated from the support 1 by washers 12 which are interposed between the socketed lugs of the casing section 8 and bosses 1^a formed on the support. And said casing section is electrically insulated from the screws 10 and 11 by washers 13, 13 the 65 edges of which engage the socket walls of the lugs 8^a, 8^b and hold them out of engagement with the shanks of the screws, said shanks being smaller in diameter than the apertures of the lugs through which they pass.

Between the lug 8^b and the head of the screw 11 is arranged a conductor terminal fitting 14 which is in electrical contact with the casing section 8 but by engagement of 70 its flange 14^a with the aperture of the lug 8^b is held out of contact with the screw 11. This terminal fitting 14 is formed with an upturned flange or lug 14^b in the aperture of which is soldered the end of the insulated conductor 15. The fitting 14 is also formed with a flange 14^c which is curled around the end of the insulation 15^b of the conductor and serves to hold the latter in position and protect the soldered joint from undue 75 stresses.

The casing section 9 which overlies the lower end of the condenser is secured to the support 1 by screws 16, 17 which pass through the apertured lugs 9^a, 9^b and by 80 engagement therewith serve to electrically connect the section 9 to the support.

A spring 18 is preferably interposed between the upper clip 5 and the flanges 8^c, 8^d of the casing section 8, and a similar 85 spring 19 is interposed between the bottom clip 6 and the flanges 9^c, 9^d of the casing section 9. These springs, which are preferably made of phosphor bronze stock 0.02" 90 thick, serve to maintain a constant pressure 95

on the clips 5 and 6 so as to prevent their displacement from the ends of the condenser pack. Between the clips 5 and 6, on the outer face of the condenser pack is placed 5 a filler sheet 20 of any suitable insulating material.

In assembling and mounting the condenser, the pack comprising the two sets of conductor sheets and the dielectric sheets are 10 piled up and the extending ends of the sheets 2 and 3 are folded over and the clips 5 and 6 are applied to them. The resulting pack is then laid upon the support, the insulating sheet 7 having first been placed 15 in position. The spacer or filler sheet is then placed in position on the pack. Then the springs 18 and 19 are applied to the clips 5 and 6 and the casing sections are placed in position. Then the various insulating washers and the conductor terminal fitting 14 are placed into position and the securing screws applied. The casing sections 8 and 9 are formed with a normal 20 curve or bow, as shown in Fig. 3. Thus 25 when the securing screws are turned home, as shown in Fig. 4, an effective pressure of the casing sections 8 and 9 on the condenser pack is insured throughout its entire width.

With the parts thus assembled and mounted 30 it will be seen that the set of conductor sheets 2 are electrically insulated from the support 1 and are electrically connected through the clip 5, the casing section 8 and the terminal fitting 14 to the conductor 35 15 which is designed to lead to one terminal of the breaker of the magneto. On the other hand, the other set of conductor sheets 3 is electrically connected through clip 6, casing section 9 and screws 16, 17 with the magneto 40 frame 1 and thence to ground.

It will be seen that I have provided a condenser, the main conductor sheets and dielectric sheets of which are maintained 45 intact and free from perforations of any sort. It will also be noted that no reliance is placed upon soldered joints for electrically connecting the conductor sheets but that they are mechanically secured in electrical contact by strong and simple parts which 50 can be relied upon to remain under all conditions in proper working order. It is further obvious that the condenser can be assembled and mounted easily and quickly.

While the construction illustrated is that 55 which I prefer, it is to be understood that there can be various modifications without departing from the invention, the scope of the invention being indicated in the appended claims.

60 What I claim is:

1. In a condenser, the combination of a support, a pack of condenser elements comprising two sets of sheet conductors of metal foil and dielectric sheets between the conductors, with alternate conductor sheets 65

forming one of said sets extending at one end of the pack and the other set of conductor sheets extending at the other end of the pack, clips of flexible sheet metal embracing the ends of the pack and engaging the bent over ends of the conductor sheets, resilient means for constantly pressing the clips into engagement with the ends of the pack, and means for securing the entire structure to the support. 70

2. In a condenser, the combination of a support, a pack of condenser elements comprising two sets of sheet conductors of metal foil and dielectric sheets between the conductors, with alternate conductor sheets 75 forming one of said sets extending at one end of the pack and the other set of conductor sheets extending at the other end of the pack, resilient means for pressing together the extending ends of the pack, respectively, and current-conducting means for clamping the extending conductor sheets together and securing the entire structure to the support. 80

3. In a condenser, the combination of a pack of condenser elements comprising two sets of sheet conductors of metal foil and dielectric sheets between the conductors with alternate conductor sheets forming one of said sets extending at one end of the pack and the sheets of the other set of conductor sheets extending at the other end of the pack, and means for mechanically clamping the extending conductor sheets of each 85 set together, said means comprising resilient means for constantly exerting pressure on the pack endwise thereof and being provided with at least one conductor terminal fitting. 90

4. In a condenser, the combination of a support, a pack of condenser elements comprising two sets of sheet conductors of metal foil and dielectric sheets between the conductors with alternate conductor sheets 100 forming one of said sets extending at one end of the pack and bent over on the side thereof and the other set of conductor sheets similarly extending and bent over at the other end of the pack, clips of flexible sheet metal embracing the ends of the pack respectively and engaging the bent over ends of the conductor sheets, casing sections secured to the support and engaging the clips to clamp them in firm contact with the conductor sheets, at least one of said casing sections having a conductor terminal fitting. 105

5. In a condenser, the combination of a support, a pack of condenser elements comprising two sets of sheet conductors of metal foil and dielectric sheets between the conductors with alternate conductor sheets 110 forming one of said sets extending at one end of the pack and bent over on the side thereof and the other set of conductor sheets similarly extending and bent over at the other end of the pack, clips of flexible sheet metal 115 embracing the ends of the pack respectively and engaging the bent over ends of the conductor sheets, casing sections secured to the support and engaging the clips to clamp them in firm contact with the conductor sheets, at least one of said casing sections having a conductor terminal fitting. 120

125

other end of the pack, clips of flexible sheet metal embracing the ends of the pack respectively and engaging the bent over ends of the conductor sheets, metal casing sections

5 each of which overlies one end of the pack, resilient means between each of said clips and the end wall of the adjacent casing section, and means for securing the casing sections to the support and pressing the clips 10 and conductor sheets into effective electrical contact, at least one of the casing sections having a conductor terminal fitting.

6. In a condenser, the combination of a support, a pack of condenser elements comprising two sets of sheet conductors of metal foil and dielectric sheets between the conductors with alternate conductor sheets forming one of said sets extending at one end of the pack and bent over on the side 15 thereof and the other set of conductor sheets similarly extending and bent over at the other end of the pack, metal casing sections one of which overlies each end of the pack and one set of bent over conductor sheets to 20 clamp the pack to the support, one of said casing sections being formed with sockets and apertures in the bottoms of said sockets, screws of smaller diameter than said apertures extending therethrough into the support, and insulating washers between the 25

30

casing section and the screw heads and engaging said sockets to hold the casing section out of contact with the screws.

7. In a condenser, the combination of a support, a pack of condenser elements comprising two sets of sheet conductors of metal foil and dielectric sheets between the conductors with alternate conductor sheets forming one of said sets extending at one end of the pack and bent over on the sides 35 thereof and the other set of conductor sheets extending at the other end of the pack, a metal casing section overlying the pack and bent over sheets to clamp the pack to the support, said casing section being formed 40 with sockets and apertures in the bottoms of said sockets, screws of smaller diameter than said apertures extending therethrough into the support, insulating washers between the 45 casing section and screw heads and engaging 50 said sockets to hold the casing section out of contact with the screws, and an apertured conductor terminal fitting disposed in one of said sockets between the casing section and an insulating washer and held by engagement with the casing section out of contact 55 with the screw passing through its aperture.

In testimony whereof, I hereunto affix my signature.

CARL E. PEARSON.
